UNITED STATES PATENT OFFICE.

ADA R. JONES, OF BOZEMAN, MONTANA.

DESIGN FOR A TOY DOG.

Application filed March 14, 1921. Serial No. 452,346. Term of patent 14 years.

To all whom it may concern:

Be it known that I, ADA R. JONES, a citizen of the United States, residing at Bozeman, in the county of Gallatin and State of Montana, have invented a new, original, and ornamental Design for a Toy Dog, of which the following is a specification, reference being had to the accompanying drawing, forming part thereof.

I claim:

The ornamental design for a toy dog as shown.

ADA R. JONES.
